[57] CLAIM

The ornamental design for a loader tooth for a front end loader, as shown and described.

DESCRIPTION

FIG. 1 is a side perspective view of a loader tooth for a front end loader showing my new design;

FIG. 2 is a side perspective view thereof, opposite that seen in FIG. 1;

FIG. 3 is a top perspective view thereof;

FIG. 4 is a perspective view taken from the left of FIG. 1.

FIG. 5 is a bottom plan view thereof.

FIG. 1

FIG. 2

FIG. 3

FIG. 4

FIG. 5
